(57) **CLAIM**

The ornamental design for a surgical saw blade hub, as shown and described.

DESCRIPTION

FIG. 1 is a perspective view of a surgical saw blade hub showing our new design;

FIG. 2 is a top plan view thereof, the bottom plan view being a mirror image thereof;

FIG. 3 is a side elevational view thereof, the opposite side elevational view being a mirror image thereof; and,

FIG. 4 is a rear elevational view thereof.

The broken lines showing of the cutting portion of the surgical saw blade are for illustrative purposes only, and form no part of the design.
